Primary Examiner — Caron D Veynar*Assistant Examiner* — Abraham Bahta(74) *Attorney, Agent, or Firm* — Knobbe Martens Olson & Bear, LLP**CLAIM**

The ornamental design for a merchandise return label for international returns, as shown and described.

DESCRIPTION

FIG. 1 is a top view of a first embodiment of a merchandise return label in accordance with the present invention; and, FIG. 2 is a top view of a second embodiment of a merchandise return label in accordance with the present invention.

The broken line of the label edge and the broken line showing of certain words and symbols in the drawing are for illustrative purposes only and form no part of the claimed design.
